UNITED STATES PATENT OFFICE

170,242

FRONT PLATE FOR A CIRCULATING FIREPLACE HEATER

Albert P. Robinson, Seattle, Wash.

Application May 16, 1952, Serial No. 19,752

Term of patent 14 years

(Cl. D81—7)

To all whom it may concern:

Be it known that I, Albert P. Robinson, a citizen of the United States, residing at Seattle, in the county of King and State of Washington, have invented a new, original, and ornamental Design for a Front Plate for a Circulating Fireplace Heater, of which the following is a specification, reference being had to the accompanying drawing, forming a part thereof.

Fig. 1 is a front elevation of a front plate for a circulating fireplace heater embodying my new design.

Fig. 2 is a side elevation of the same.

Fig. 3 is a top view of the same.

I claim:

The ornamental design for a front plate for a circulating fireplace heater, as shown.
ALBERT P. ROBINSON.
